APPARATUS FOR FORMING FIBER SHEETS

Henry W. Piquet, Moorestown, N. J., assignor to
MacAndrews and Forbes Company, Camden,
N. J., a corporation of New Jersey

Application January 29, 1932. Serial No. 589,732

5 Claims. (Cl. 92—42)

This invention relates to new and useful improvements in apparatus for use in the formation of relatively thick fibre sheet and particularly in the formation of insulating sheet, wall board, or the like.

5 The principal object of the invention is to provide apparatus of the character set forth having certain novel features of construction affording a fibre sheet having a substantially smooth surface texture.

10 Another object of the invention is to provide apparatus as set forth having certain novel features of construction capable of forming fibre sheets of substantially greater uniformity or more dense fibre structure.

15 Another object of the invention is to provide apparatus as set forth whereby sloughing of the fibre stock from the cylinder prior to engagement by the pressure means, is eliminated.

20 Another object of the invention is to provide apparatus as set forth having a novel idling or smoothing roller.

Another object of the invention is to provide apparatus as set forth having novel means for alleviating vacua created adjacent the idling or 25 smoothing roller.

Another object of the invention is to provide apparatus as set forth embodying a novel feed arrangement for the sheet stock to the machine 30 for the purpose of affording better agitation thereof prior to the formation of the fibre sheet.

Other features and details of the invention are disclosed hereinafter and shown in the accompanying drawing, in which:

35 Figure 1 is a transverse sectional view of the apparatus constituting the invention; and

Fig. 2 is a fragmentary view in perspective showing the novel construction of the idling or smoothing roller.

40 Referring now particularly to the drawing, the present apparatus embodies a conventional form of cylinder machine comprising a vat 1 carrying the stock in which rotates the forming cylinder 2.

45 The interior of the forming cylinder is equipped with customary suction apparatus by means of which the degree and application of suction in various regions on the surface of the cylinder may be controlled. The suction apparatus is of usual

50 construction and need not be illustrated and described in detail. A continuous wire belt 3 is provided and is carried by the rollers 4 and the idling roll 5 for the purpose of pressing the wet web to extract the water therefrom and to substantially smooth the surface texture of said web

in advance of the point where the web leaves the cylinder.

In the present instance the particular feature of the invention resides in positioning the idling roller 5 entirely below the surface of the stock in the vat 1. By positioning the idling roller 5 in the manner set forth, the fibres of the wet web ultimately formed will be laid and the texture of the web formed, prior to emerging from the vat.

The wet web produced in the above manner embodies a body structure of greater uniformity and fibre density having an extremely smooth surface texture, than similar machines have been capable of producing heretofore. Furthermore, by positioning the idling roller 5 below

the surface of the stock, there is no interval, prior to the contact of the belt 3 with the wet web, after the web emerges from the vat 1, to permit a tendency for the stock to slough back into the vat from the cylinder, as in a majority of machines.

The roller 5 in the present instance is so positioned, radially of the cylinder 2, as to effect a gradual application of the pressure of the wire belt 3 upon the web, just prior to emerging from the vat 1, on the cylinder 2, thus eliminating the sudden application of the total pressure of the belt, which tends to destroy the already formed surface texture of the wet web and is most undesirable.

It has been found, by positioning the ordinary cylindrical roller having a solid surface, beneath the surface of the sheet stock, there is a tendency for said stock to become lodged within the roller, necessitating periodic removal thereof for purposes of cleaning.

To eliminate the above undesirable feature, a roller or pulley of the type disclosed in Fig. 2 of the drawings is positioned beneath the surface of the stock. This roller or pulley designated generally as at 5 is of relatively open construction having the spaced longitudinal members 6 thereof disposed with respect

90 to the shaft 7 by means of the spokes 8. By the construction set forth the stock mix residing about the roller 5 is kept in continuous agitation which prevents the said stock becoming dry and adhering to the roller. A shower or spray 9 is disposed above the roller 5 and functions to flush any stock in said roller back into the vat proper.

The spray or shower 9 functions in a second capacity to dilute the stock in the vat adjacent the pulley 5 and eliminate any tendency for said stock becoming viscous, due to lack of water content which has a tendency to be drawn from

95 said stock, through the web on the cylinder 2, by the suction in said cylinder, that is, the amount of water supplied to the stock by the shower 9

must be sufficient to compensate for the water drawn from the stock by the suction, in order that the stock adjacent the pulley 5 will be maintained at the required uniform water content.

- 5 For the purpose of effecting a more thorough and continuous agitation of the fibre stock in the vat 1, it has been found advantageous to feed the stock into the vat in a direction opposite to the direction of rotation of the cylinder 2.
- 10 The fibre stock is fed from a hopper or chute 10 against a baffle element 11 which is arranged to deflect the flow of the stock away from the idling roller 5 and the wire belt 3 along a course adjacent the inner surface of the vat 1 to the position where the stock adheres to the surface of the cylinder 2 by the action of the suction internally thereof.

Fibre web formed in the manner, and by means of the apparatus, herein disclosed, is of greater uniformity and of relatively smoother surface texture than has heretofore been obtainable, and affords a product of more finished appearance and greater desirability in the open market.

While a particular embodiment of the invention has been disclosed herein for the purpose of description, it is not intended to be limited thereto except as set forth in the appended claims.

I claim:

- 30 1. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, and means passing about said roll contacting with the web for a predetermined length of travel beginning at a point below the surface of the stock in the vat.
- 35 2. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and water passable means passing about said roll contacting with the web for a predetermined length of travel beginning at a point below the surface of the stock in the vat.
- 40 3. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and water passable means passing about said roll contacting with the web for a predetermined length of travel beginning at a point below the surface of the stock in the vat.
- 45 4. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and water passable means passing about said roll contacting with the web for a predetermined length of travel beginning at a point below the surface of the stock in the vat.
- 50 5. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and water passable means passing about said roll contacting with the web for a predetermined length of travel beginning at a point below the surface of the stock in the vat.

roll contacting with the web for a predetermined length of travel beginning at a point below the surface of the stock in the vat.

3. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and water passable means passing about said roll contacting with the web for a predetermined length of travel beginning at a point below the surface of the stock in the vat.

4. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and water passable means passing about said roll contacting with the web for a predetermined length of travel beginning at a point below the surface of the stock in the vat.

5. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, and pressure means passing about said roll contacting with the web for a predetermined length of travel beginning at a point below the surface of the stock in the vat, the said pressure means being arranged to gradually apply pressure to said web and prevent sloughing of the stock from the surface of the cylinder to the vat.

5. Apparatus for forming a fibre web from substantially viscous stock comprising in combination, a stock vat, a suction forming cylinder arranged for rotation and forming a continuous wet web of substantial thickness, a skeleton return roll mounted for rotation in the vat at a point below the surface level of the stock therein, the said roll being of substantially open construction whereby clogging of the roll by the stock is precluded, water passable means passing about said roll contacting with the web for a predetermined length of travel beginning at a point below the surface of the stock in the vat, and means adjacent one end of said pressure means to deflect stock fed to said vat from the path of said pressure means.
